UNITED STATES PATENT OFFICE.

ADOLPH WAHLE, OF DAVENPORT, IOWA, ASSIGNOR TO DAVENPORT WASHING MACHINE COMPANY, OF DAVENPORT, IOWA, A CORPORATION OF IOWA.

GEARING.

1,037,690.

Specification of Letters Patent. Patented Sept. 3, 1912.

Application filed June 3, 1912. Serial No. 701,440.

To all whom it may concern:

Be it known that I, ADOLPH WAHLE, a citizen of the United States, and a resident of the city of Davenport, county of Scott, 5 State of Iowa, have invented certain new and useful Improvements in Gearing; and I do hereby declare that the following is a full, clear, and exact description thereof, reference being had to the accompanying 10 drawings, and to the letters of reference marked thereon, which form a part of this specification.

This invention relates to an improvement 15 in gearing and consists of the matters hereinafter described and more particularly pointed out in the appended claims.

The improvement in gearing, as shown herein, is applied to a washing machine and is used for imparting rotary reciprocatory 20 movement to the familiar dolly-shaft of a washing machine.

In the drawings:—Figure 1 represents a side elevation of a washing machine provided with my improved gearing. Fig. 2 25 is a view showing a partial vertical section on an enlarged scale through the gearing in a plane indicated by the line 2—2 of Fig. 1. Fig. 3 is a view representing a top plan 30 view of the washing machine. Fig. 4 is a view representing a detail perspective of a reciprocating rack-plate to be more particularly referred to later.

Referring now to that embodiment of my invention illustrated in the drawings, 10 indicates a support, in this case a washing machine tub comprising a tub 10^a supported on upright legs 11, 11, which are held in proper spaced relation by diagonally-arranged cross-bars 11^a, 11^a. The tub is provided with 15 a top comprising spaced, parallel, fixed marginal parts 12, 12, a fixed marginal part 12^a, arranged at right angles to the first-named marginal parts, and a lid 12^b hinged to the fixed marginal part 12^a and adapted 20 to close the space between the parallel marginal parts 12, 12.

13 (see Fig. 2) indicates a dolly-shaft which depends into the tub and carries a beater 13^a at its lower end. Said 25 shaft has bearing in an upright sleeve 14 made integral with a horizontal bearing plate 15 attached to the top of the hinged lid 12^b. Said sleeve extends above and below said bearing plate 15, at its lower end,

extending into an aperture in the hinged lid 12^b. The shaft 13 projects above the sleeve 14 and has there fixed to it a beveled gear 16 which bears upon the upper end of the sleeve.

17 indicates a horizontal shaft rotatively 60 mounted in upright bearing arms 15^a, 15^a, rising from the plate 15. A beveled gear 18 is pinned to the inner end of the shaft 17 and meshes with the beveled gear 16. A spur-gear 19 is pinned to the outer end of 65 the shaft 17. Said beveled gear 18 and spur gear 19 have hubs 18^a, 19^a, respectively, which have thrust bearing on opposite sides of the associated bearing arms 15^a, 15^a, so as to hold the shaft 17 against longitudinal 70 movement.

On the fixed marginal part 12^a of the tub top is secured a bearing plate 20, which extends nearly the full length of said fixed part and has a longitudinal flange 20^a at 75 one edge which is located at or adjacent to the inner edge of the said fixed part.

21 indicates a reciprocating rack-plate having upright rack-teeth 21^a formed adjacent one edge. The edge of said rack-plate in 80 which the teeth are formed engages against the upright flange 20^a of the bearing plate. In the top surface of the rack-plate near its other edge is formed a longitudinal, rectangular groove 21^b in which engages a depending longitudinal rib 22^a formed on the bottom surface of an upper bearing plate 22 that has bearing engagement with the rack-plate and is adapted to hold the same down 85 on the lower bearing plate 20. Said upper bearing plate 22 has at each end a depending flange 22^b at the lower edge of which is formed a horizontal flange 22^c resting upon the top of the plate 20. Said plates 22 and 20 are secured to the part 12^a of the tub top 90 in any convenient manner, as by means of bolts or screws 23, which extend through the horizontal flanges 22^c and through the end marginal parts of the plate 20.

The rack-plate 21 is provided intermediate its ends with a laterally extending web 21^c which carries a pin 21^d. On said pin 21^d is pivotally mounted one end of a pitman 24 which is adapted to impart reciprocating movement to the rack 21 by 105 mechanism presently to be described. It is apparent that by reciprocating the rack-plate 21 a rotary, oscillatory movement will

be imparted to the spur-gear 19 and through it to the shaft 17, the beveled gears 18 and 16, and to the dolly-shaft 13.

The upper bearing plate 22 has upright apertured arms or lugs 25, one located near each end. Associated arms or lugs 26, 26 are secured to the hinged top 12^b and are provided with spaced pairs of apertured lugs 26^a, 26^a, each pair being adapted to 10 embrace one of the lugs 25 and being hinged thereto by means of a suitable bolt or screw. The lugs 25 and arms 26 thus comprise the two leaves of the hinges by means of which the part 12^b of the tub top is hinged to the 15 fixed marginal part 12^a thereof. The parts are so arranged that the common axis of the hinges is located above and back of the plane of the rack-teeth 21^a so that when the hinged part 12^b of the tub top is swung upwardly on its hinges, the spur-gear 19 carried thereby will move away from engaging 20 position with the teeth in the rack-plate without binding.

The spur-gear 19, shaft 17, and beveled 25 gears 18 and 16 are protected by a gear case 27 which is formed to inclose said parts, as clearly shown in the drawings, and is provided with laterally disposed, horizontally spaced pairs of apertured lugs 27^a, by 30 means of which it is secured to the hinged top of the tub. Said gear casing prevents the clothes of the operator from becoming entangled in the gearing.

Located in a plane back of the tub and extending parallel to the shaft 17 carried by the hinged tub lid, is a main driving shaft 28, which, as shown, is in length equal substantially to the diameter of the tub and has bearing in plates 29, 30 attached to the tub body near the ends of said shaft. The shaft 40 28 has rigidly secured to it a pulley 31. The pulley 31 is adapted to be driven from a suitable source of power and, as shown herein, said pulley is connected by a belt 32 to 45 the driving pulley 33 of an electric motor 34 supported below the tub body. Said motor is carried on a baseboard 35 secured in the angle of the cross-braces 11^a, 11^a that brace the tub legs apart.

50 A pinion 36 is keyed to the shaft 28 adjacent the pulley 31, said pinion meshing with a large gear 37 fixed to a shaft 37^a that extends parallel to the main driving shaft 28 above the tub top and has bearing 55 near its ends in the plates 29 and 30. On the face of the gear 37 is provided a crank-pin 37^b with which the pitman 24 has pivotal connection so that the continuous rotation of the gear 37 in one direction will impart 60 through the pitman 24 a reciprocating, longitudinal, sliding movement to the rack-plate 21. The pinion 36 and the gear 37 are protected by a casing or shell 37^c which incloses them, and is attached to the bearing plate 29.

65 The gearing described herein is simple in

construction and efficient in operation. All of the gearing is amply protected so that it is particularly adaptable for use in power washing machines which are usually operated by women and must, therefore, be especially free from the possibility of clothing or parts of the body being caught between engaging gear teeth.

70 By reason of the arrangement and construction of the hinges of the lid, as described, an increased clearance at the end of the dolly shaft is provided when the hinged lid is in open position so that ample room is afforded for passing the clothes from the tub to the wringer when a wringer is used.

75 The flange 20^a on the bearing plate 20 under the reciprocating rack-plate 21 makes it possible to thoroughly oil the bearings of said rack-plate without danger of the oil dripping into the tub since said flange 20^a 80 will retain the oil on the bottom plate 20.

85 While in describing one embodiment of my invention, I have shown and described certain details of mechanical construction and arrangement, it is to be understood that 90 my invention is in no way limited except as pointed out in the appended claims.

I claim as my invention:—

1. In combination with a support, a continuously rotative shaft carried thereby, a member hinged to said support, an operating shaft carried by said hinged member extending parallel to said continuously rotative shaft, a rack-plate carried by said support below the plane of said operating shaft and adapted for longitudinal reciprocation at right angles to said operating shaft, said rack-plate having upright teeth, a gear fixed to said operating shaft and in mesh with said rack-teeth and means for converting the continuous rotative movement of the first-named shaft into the longitudinal reciprocatory movement of said rack-plate.

100 2. In combination with a support, a continuously rotative shaft carried thereby, a member hinged to said support, an operating shaft carried by said hinged member extending parallel to said continuously rotative shaft, a rack-plate carried by said support below the plane of said operating shaft and 105 adapted for longitudinal reciprocation at right angles to said operating shaft, said rack-plate having upright rack-teeth adjacent its margin near said hinged member, a gear fixed to said operating shaft in mesh with said upright rack-teeth, means for hinging said hinged member to said support with the axis of the hinge located above and back of the vertical plane of said rack-teeth, and means for converting the continuous rotative movement of the first-named shaft into a reciprocatory movement of said operating shaft.

110 3. In combination with a support, a continuously rotative shaft carried thereby, a 115

member hinged to said support, an operating shaft carried by said hinged member extending parallel to said continuously rotative shaft, a rack-plate carried by said support 5 below the plane of said operating shaft, and adapted for longitudinal reciprocation at right angles to said operating shaft, upper and lower bearing plates carried by said support between which said rack-plate has sliding bearing, the lower plate having an upright flange adapted for engagement with the inner edge of said rack-plate and the

upper bearing plate having a depending longitudinal rib engaged within a longitudinal groove in the upper surface of the 15 rack-plate.

In testimony, that I claim the foregoing as my invention I affix my signature in the presence of two witnesses, this 28th day of May, A. D. 1912.

ADOLPH WAHLE.
